UNITED STATES PATENT OFFICE.

CHARLES E. CARPENTER, OF PHILADELPHIA, PENNSYLVANIA.

ARMCHAIR ASH RECEIVER.

Application filed January 26, 1920. Serial No. 354,023.

To all whom it may concern:

Be it known that I, CHARLES E. CARPENTER, a citizen of the United States, residing at Philadelphia, in the county of Philadelphia and State of Pennsylvania, have invented certain new and useful Improvements in Armchair Ash Receivers, of which the following is a specification.

The invention relates to ash receivers, for smokers' use, attached or adapted to be attached to the under sides of the arms of chairs and the like, for the purpose of affording a convenience to the smoker and preventing the littering of floors and porches with ashes and stubs of cigars and cigarettes.

It is a principal object of the invention to make the device substantially air tight so that it will be odorless, it being well known that the odor from the remains of cigars and cigarettes, after they are extinguished, is quite disagreeable. This object is accomplished by the construction of the pivotal support of the receiver so that the edge of the ash receptacle will be always held in tight contact with the under side of the chair arm when the device is in closed position, that is to say, when it is swung under the chair arm. This contact has also a yielding frictional character so that said pivotal connection will keep the device in place when it is closed and the receiver can not be spilled by the moving of the chair to which it is attached.

With such objects in view, as well as other advantages which may be incident to the use of the improvements, the invention consists in the parts and combinations thereof, hereinafter set forth and claimed, with the understanding that the several necessary elements constituting the same may be varied in proportions and arrangement without departing from the nature and scope of the invention.

In order to make the invention more clearly understood there are shown in the accompanying drawings means for carrying the same into practical effect, without limiting the improvements, in their useful applications, to the particular constructions which, for the purpose of explanation, have been made the subject of illustration. In the said drawings:—

Fig. 1 is a vertical sectional view of the receiver on line I—I of Fig. 2, showing also

a portion of the chair arm to which the receiver is attached.

Fig. 2 is a plan view of the same.

Fig. 3 is a vertical sectional view on line III—III of Figure 2 of the swinging arm 60 and spring before the parts have been attached to the chair arm.

Referring to the drawings, 1 indicates a portion of a chair arm or the like to which the receiver is applied. The receiver comprises a supporting arm 2, a removable cup 3, a pivot and adjusting screw 4 and a friction and regulating spring 5.

The arm is preferably of cast metal comprising a ring 6 formed at its lower part 70 with an inwardly extending flange or ledge 7. Cast with said ring is a laterally extending arm 8 formed with a pivot hole 9 and a spring socket 10 in its upper side.

The cup 3 for the reception of ashes and the like is formed with a lip or outwardly extending flange 12 adapted to rest upon the ledge 7 of the ring and be inclosed by the main portion of the ring. The flange of the cup is of a little greater depth than 80 the depth of the ring portion above the flange 7, whereby the edge of the cup will itself bear against the under side of the chair arm, as shown in Fig. 2.

The pivot screw 4 passes through the aperture 9 and the head of the screw keeps the device in place with the edge of the cup in contact with the under side of the chair arm, excepting when the receiver has been swung out from under the chair arm into position 85 for use. This screw has a regulating function, it being screwed in to the chair arm until the edge of the cup is brought into the described even engagement therewith, but it does not clamp the ring against said arm. 90 The spring 5 is arranged around the screw in the socket 10 so as to hold the under side of the arm 2 tightly against the head of the screw, the upper side of the spring bearing with a frictional contact on the under 100 side of the chair arm. The spring is of conical spiral form so as to give a broad bearing at its upper side against the chair arm and so as to give a narrow bearing at its lower end on the receiver arm, whereby the 105 latter may tilt on the spring as may be required to give the edge of the receiver its proper tight bearing against the chair arm.

In the operation of the device the cup and ring are swung out from under the chair 110

arm so as to expose the receiver for use. At this time the friction produced by the spring, socket and screw will maintain the device in adjusted position without any 5 looseness, the friction taking place between the spring and the chair arm or between the lower end of the spring and the socket. When the device is not in use it is to be 10 swung under the chair arm whereupon the edge of the receiver will take a tight bearing against the same, and the additional friction of the edge of the receiver on the chair arm will keep the device closed notwithstanding any handling and moving of 15 the chair.

The small lower end of the spring has what is in effect a universal bearing in the socket 10, which enables the supporting arm and ring to tilt in any direction relative 20 to a horizontal plane so that the edge of the cup will have the tight closure on the under side of the chair arm as described. Also the under side of the flange 12 of the cup is or may be rounded as indicated at 25 14 which produces in effect a universal ball and socket joint between the ring and cup and facilitates any necessary movement of the cup in taking its described tightly closed position. It will be understood that my improvement overcomes any difficulties arising 30 from the under side of the chair arm not being a perfectly plane surface, or arising from a warping of the arm from exposure to the weather or from drying, so that I 35 obtain a tight closure of the cup, as desired, notwithstanding said inequalities in the wood of the arm.

In applying the device the pivot screw is screwed up into the under side of the 40 arm of the chair or other support so as to somewhat compress the spring and until the edge of the cup is brought to the proper tight bearing. Thereafter the parts will maintain the adjusted relation and will operate 45 with the necessary friction to keep the cup

open or closed. In case of wear the screw is to be slightly tightened.

I have described the device in connection with a chair arm, such application probably being the widest sphere of usefulness of the 50 invention, but it will be understood that the invention is not restricted to such particular use and may be applied to tables, desks and the like.

What is claimed is:—

1. In an ash receiver the combination of 55 a suitable support, an arm pivotally connected with the under side of said support, a cup carried by said arm and adapted to be swung out from and also under said support, and a spring bearing on said arm and adapted to permit a movement of the arm to cause a tight closure of the cup by means of the under side of said support.

2. In an ash receiver the combination of 60 65 a suitable support, an arm pivotally connected with the under side of said support, a cup carried by said arm and adapted to engage the under side of the support, and a conical spiral spring bearing on the under 70 75 side of the support with its larger end and also on said arm with its smaller end and adapted to permit a movement of the arm to cause a tight closure of the cup against the under side of said support.

3. In an ash receiver the combination of 80 85 a suitable support, an arm pivotally connected with the under side of said support and spaced therefrom, a cup carried by said arm and adapted to engage the under side of the support, and a spring bearing on the under side of the support and also on said arm, said cup having a substantially universal movement of self-adjustment relative to said support to cause a tight closure of the cup against the under side of said support.

In testimony whereof I affix my signature.

CHARLES E. CARPENTER.
